CLAIM

I claim the ornamental design for a sole of a footwear article, as shown and described.

DESCRIPTION

FIG. 1 a bottom, side perspective view of a sole of a footwear article;

FIG. 2 is a bottom view of the sole of a footwear article of FIG. 1; and,

FIG. 3 is a side view of the sole of a footwear article of FIGS. 1.

The ornamental design that is claimed is shown in the drawings.

The broken lines in FIG. 2 depict unclaimed portions of the sole of a footwear article and form no part of the claimed design.
